UNITED STATES PATENT OFFICE.

ELIJAH F. DUNAWAY, OF COVINGTON, KENTUCKY.

FIRE-PLACE HEATER.

SPECIFICATION forming part of Letters Patent No. 351,025, dated October 19, 1886.

Application filed October 23, 1884. Serial No. 146,327. (No model.)

To all whom it may concern:

Be it known that I, ELIJAH F. DUNAWAY, a citizen of the United States, and a resident of Covington, in the county of Kenton and State 5 of Kentucky, have invented certain new and useful Improvements in Fire - Place Heaters, of which the following is a specification.

This invention is an improvement in fire-place grates and heating-stoves.

Its object is to control combustion, prevent smoke, and insure the radiation into the room or chamber of the heat produced by the combustion of the fuel.

With these objects in view my invention 15 consists in a peculiar arrangement of revolving fire-basket having pivoted gates forming parts of the same upon opposite sides of the axis, whereby fuel may be alternately introduced and the grate given a half-revolution to 20 bring the incandescent fuel upon top.

It consists, also, in a peculiar arrangement of heating-chamber and fire-back with means for introducing heated air into the fire-box to promote combustion, and also into the room, 25 instead of allowing it to pass through the flue.

It also consists in certain novel details of construction and combination of parts, all of which will be fully understood from the following description of the accompanying drawings, in which—

Figure 1 is a front elevation of a fire-place grate provided with my improvements. Fig. 2 is a central vertical section of the same. Fig. 3 is an axial section of my improved grate, 35 showing another means of suspending the same. Fig. 4 is a perspective view of the cap or plate which closes a portion of the chimney-opening and forms the flue. Fig. 5 is a view of my improved grate or fire - basket, 40 taken at right angles to the view shown in Fig. 3, and also showing my preferred means to mount or suspend the grate in place. Fig. 6 is a front elevation of a stove provided with my improvements. Fig. 7 is an elevation of 45 the same with a perforated back cap, shown in vertical section.

The grate front or frame A, with its hood, a, may be made of any suitable design or pattern. It is cast hollow at the back and has 50 perforations to permit the passage of heated air into the room. Secured to this frame A, or cast as part of it, is the cone-shaped back

B. This back has a flue or thimble, b, which, when the grate is in place, passes into the opening in the piece C, Fig. 4. The piece C 55 has an upwardly-projecting flange, c, which has an opening to receive the flue b.

The fire-basket, Figs. 3 and 5, consists of the back D and the concavo-convex grated front E. The back is preferably corrugated to give 60 it a greater heating-surface, and the center part of the front or grate is permanently secured to it. Upon opposite sides of the center are gates or doors F, which are pivoted in lugs f, secured upon the back D. The pivot- 65 bearings are elongated, in order that the gates may be lifted up when the gate is opened, or turned back in the recess in the back D, to allow the hooks f² to catch over the rim of back D. The weight of the gate retains it in the 70 open position. When it is desired to close the gate, it is lifted up to release the catch, and when closed it is held in the closed position by the pivoted latch e, which is turned over the catch f². As shown in Fig. 2, the pivot 75 upon which the fire-basket turns is a tube, G, which has an annular recess at G' around it, near the inner end, to engage a perforated plate, b', let into the inner end of back B. The forward end of the tube is secured to the back 80 D, and is supported by a bracket, g, which rests upon the inner wall of the back B. The tube G communicates with the fire-chamber and the chamber H, which is formed by the back B, fire-place walls, and the plate C. On 85 the inside of the fire-back is a cap, d, which is perforated to permit the heated air to enter the fire-chamber in jets, to more completely mingle with the gaseous products generated in the fire-chamber, and thus promote com- 90 bustion. Air is admitted to the chamber H through a flue, h, which is controlled by a reg- 95 ister, h', underneath the ash-box. The front of the grate is provided with folding doors I, which when opened, as seen in Fig. 1, serve the double purpose of radiating the heat into 100 the room and protecting the mantel and fire-front A. On the center of the bottom plate is an upwardly-projecting lug, i, back of which the lower front corners of the middle doors slide as they are closed. The doors are held closed by gravitating bolts J. The doors are opened by placing the end of a poker or the key K in the upper looped end of the bolts J,

raising the bolt. Then as the side door is swung back on its hinges the free end of the center door slides out of engagement with the lug or button *i*. The basket, as shown in Fig. 2, is inserted by inclining the inner end of the tubular pivot downward until the annular notch *G* around the inner end comes beneath the plate *b* in the back *D*. Then by letting the basket down until the pivot assumes a horizontal position and rests on the semicircular bearing of the bracket *g* its weight will prevent its being withdrawn until lifted up.

To provide against any accidental displacement of the revolving fire-basket, I form a pivot, *e*, which passes through a brace, *L*, (shown in dotted line, Fig. 1,) which brace extends across the grate and has its ends secured to the front flange of the back *B*. The pivot *e* has an angular key-seat to receive the angular end of the key *K*, by which the grate is revolved upon its axis. In my preferred means of securing the basket in place, as shown in Fig. 5, *B* conforms to the shape of the fire-back *D*, and a supplemental piece, *B*², is secured to it, making a small chamber, *H*', between the cone end of the back piece, *B*², and the back *B*'. The back *B* has a hub, *b*², cast with it to furnish a broad bearing for the tube *G*, which is the journal upon which the fire-basket revolves. This tube is screwed into the fire-back *D*, and projects back through a central opening in the back cap, *B*². A bolt, *g*², passes through the cap *d*, and a cap, *g*³, which projects over the end of the cap *B*², and secures the parts together. When this form of fire-basket is used, the brace *L* in front of the grate may be dispensed with. The tube *G* is perforated, as is also the back cap, *B*², so that heated air may pass through the tube *G* into the fire-chamber.

In Figs. 6 and 7 I have shown a heating-stove containing my improvements. This differs in no essential features from the grate heretofore described, except that it has a perforated cap, *M*, which covers the back *B*, making an ornamental finish, and forming with the back *B* a hot-air chamber. The doors of this stove open the same as the grate, so that it may also be used as an open fire-place when desired.

My grate is used as follows: After the fire is made and the fuel, of which only about half the full supply of the grate is first used, becomes incandescent, a fresh supply is introduced through the upper gate, which is thrown back for the purpose, the upper gate is closed and latched. The grate is then turned half a revolution by the key *K*, bringing the incandescent fuel on top and the fresh fuel below. The fresh fuel in this position will undergo a coking process, and the gases arising pass through the incandescent fuel on top and receive in their passage a supply of highly-heated oxygen, which combines with them and produces perfect combustion, thus preventing smoke and utilizing the products of combustion.

I do not claim, broadly, a revolving fire-

basket, nor an arrangement of heating-chambers back of or around the fire-chamber, as both of these features are well known.

What I claim as new, and desire to secure by Letters Patent, is—

1. The combination, substantially as specified, of the revolving fire-basket consisting of the back *D*, front *E*, and pivoted gates *F*, the pivot projecting from the back *D*, and the double bearings back of the fire-basket for the pivot, to support the fire-basket and admit of its being revolved.

2. In combination with a grate constructed to revolve on horizontal bearings, the back *B*, heating-chamber *H*, inlet *h*', and hollow pivot *G*, whereby heated air is introduced into the fire-chamber, substantially as and for the purpose set forth.

3. The combination, with the main frame of a fire-place heater having a back, *D*, and horizontal bearings, of a grate-front, *E*, secured to said back, and gates *F*, pivoted upon opposite sides of said horizontal bearings, the said back being provided with recesses, and said gates being pivoted on horizontal pivots, substantially as before set forth.

4. The combination, substantially as specified, of the revolving grate or fire-basket *D* *E*, the hollow pivot *G*, the gates pivoted upon opposite sides of the pivot *G*, the said back *D* having a perforated cap, *d*, and the front *E* being provided with latches to retain the gates *F* closed when the fire-basket is revolved and the gate is on the bottom.

5. The combination, substantially as specified, of the back *B* with the back *D*, cap *B*², chamber *H*', the tube *G*, perforated to receive heated air from chamber *H*', the caps *d* and *g*³, and bolt *g*², to secure the parts together, the front *E*, and pivoted gates *F*.

6. In a fire-place having a revolving fire-basket, such as described, the combination, substantially as specified, of chamber *H*, having flue *h*, and register *h*', and cap *C*, with the back *B*, open at the cone end, and the hollow pivot *G*, communicating with the chamber *H*, and the fire-basket.

7. In a grate revolving on horizontal pivots, as described, the combination of the back *D*, having slotted lugs *f* secured to its flange, and the grate *E*, with the gates *F*, having pivots to enter said slotted lugs, hooks *f*² to engage the flange of the back *D* when the gate is thrown open, and to be engaged by latches *e* when the gates are closed, substantially as specified.

8. The combination, with the main frame of a fire-place heater having a back and horizontal bearings, of a front secured to said back, and gates pivoted on horizontal pivots to the front upon opposite sides of the horizontal bearings, substantially as before set forth.

ELIJAH F. DUNAWAY.
